(57) **ABSTRACT**

A toy vehicle track system includes a lifting apparatus, a releasing apparatus, and a stunt apparatus. The lifting apparatus includes a drive wheel rotatable to pull a carrier line attached to a carrier including a vehicle holder that is positioned for holding a toy vehicle. The release apparatus includes a stop structure attached to the track that engages the carrier to actuate calipers of the vehicle holder to release the vehicle. The stunt apparatus includes a plurality of stunt track segments attached to a rotary indexer. The rotary indexer allows the stunt track segments to be rotated about an axis that is substantially parallel to a travel direction defined by the toy track to align each of the stunt track segments individually with the toy track to form a continuous travel path.

TOY VEHICLE TRACK WITH LIFT, RELEASE AND STUNT APPARATUSES

CROSS-REFERENCE TO RELATED APPLICATIONS

The present application claims the benefit of Canadian Patent Application No. 3,177,813 filed Sep. 29, 2022, the contents of which are incorporated herein in their entirety.

FIELD

The present disclosure relates to toy tracks for toy vehicles, and more particularly to systems for lifting a toy vehicle on a vertically extending toy track, releasing the toy vehicle on the toy track, and selecting a stunt track segment for the toy track.

BACKGROUND OF THE DISCLOSURE

The prior art includes examples of toy tracks for toy vehicles: U.S. Pat. No. 3,542,366 (Schocker; Nov. 24, 1970); U.S. patent application publication no. 2005/0287918 A1 (Sheltman et al.; Dec. 29, 2005); U.S. Pat. No. 7,628,674 (Nuttall et al.; Dec. 8, 2009); U.S. patent application publication no. 2012/0220183 A1 (Payne; Aug. 30, 2012); U.S. Pat. No. 8,449,344 (Nuttall et al.; May 28, 2013); U.S. Pat. No. 8,567,690 (De La Torre; Oct. 29, 2013); U.S. Pat. No. 8,944,882 (O'Connor et al.; Feb. 3, 2015); U.S. Pat. No. 9,314,705 (Payne et al.; Apr. 19, 2016); U.S. Pat. No. 9,586,154 (Lau et al.; Mar. 7, 2017); and U.S. patent application publication no. 2018/0229137 A1 (Martinez et al.; Aug. 16, 2018).

U.S. Pat. No. 7,770,811 (Belding; Aug. 10, 2010), U.S. Pat. No. 7,946,903 (Sheltman; May 24, 2011), and U.S. Pat. No. 10,265,634 (Daly et al.; Apr. 23, 2019) disclose toy vehicle tracks with vertically extending segments. The Hot Wheels™ Track Builder Vertical Launch Kit, model no. GGH70 (Mattel, Inc., USA) includes a toy track with a vertical segment that is removably secured to a wall using Command Strips™ (3M Company; USA).

A child at the age of six years old typically has a maximum reach of about 4 feet (3.7 meters). It would be desirable for such child to be able to place a toy vehicle on and release the toy vehicle from the vertical track segment at a height beyond the child's reach.

U.S. Pat. No. 7,819,720 (Nuttall et al.; Oct. 26, 2010), and U.S. Pat. No. 8,323,069 (Nuttall et al.; Dec. 4, 2012) disclose a toy vehicle track with an indexing stunt selector having a first stunt element (i.e., a track segment) disposed in the vehicle pathway to cause a toy vehicle to perform a stunt. The stunt selector includes a turntable-like rotating element that rotates the stunt elements about a vertical axis that is perpendicular to the horizontal travel direction of the track for aligning one of the stunt elements with the remainder of the track. The Monster Jam™ Stunt Dial Playset, model no. 6060862 (Spin Master Corp.) includes a toy vehicle launcher and an indexing stunt selector. The stunt selector includes a Ferris wheel-like rotating element that rotates various stunt elements (i.e., track segments) about a horizontal axis that is perpendicular to the horizontal travel direction of the track for aligning one of the stunt elements with the remainder of the track.

Such stunt selectors require a substantial horizontal footprint or vertical clearance beyond the track surface to

accommodate the rotation of the stunt elements. It would be desirable for stunt selectors to have a more compact configuration.

SUMMARY OF THE DISCLOSURE

In a first aspect, the present disclosure provides a lifting apparatus for lifting a toy vehicle along a segment of a toy track. The lifting apparatus includes a carrier, a drive wheel, a carrier line, and a one-way clutch. The carrier includes a vehicle holder that is positioned for holding the toy vehicle, is movable toward the upper end of the segment of the toy track, and is releasably connectable to the toy vehicle. The drive wheel is rotatable relative to the segment of the toy track. The carrier line is attached to the carrier and is engageable with the drive wheel such that rotation of the drive wheel in a first drive wheel direction drives the carrier line to travel in a first carrier line direction so as to lift the carrier and the toy vehicle towards the upper end of the segment. The one-way clutch is positionable in a release position to permit of the carrier line to move in the first drive wheel direction so as to permit lifting of the carrier. The one-way clutch is also positionable in a holding position to resist movement of the carrier line in a second carrier line direction that is opposite to the first carrier line direction so as to hold the carrier against dropping.

In embodiments of the lifting apparatus, the lifting apparatus further includes a support member that supports either the drive wheel or the toy track, or both. In embodiments, the support member bears against a vertical surface, such as a wall or a door. At least part of the drive wheel is disposed horizontally between the segment of the toy track and the vertical surface.

In embodiments of the lifting apparatus, the lifting apparatus further includes a support member that rotatably supports the drive wheel. In embodiments, the segment of the toy track is supported on a horizontal surface, and the support member does not contact the horizontal surface. In embodiments, the support member may at least partially support the toy track. In embodiments, the support member is removably attached to a vertical surface adjacent to the segment of the toy track. The support member may include a first part that includes a planar surface that is removably attached to the vertical surface, and a second part extending horizontally from the first part and releasably attached by interference fit to the first part. The support member may be removably attached to the vertical surface by stretch releasing adhesive tape.

In embodiments of the lifting apparatus, the lifting apparatus further includes a handle for manually rotating the drive wheel.

In embodiments of the lifting apparatus, the lifting apparatus further includes segment of the toy track, and the toy track defines a gap for receiving the carrier line.

In embodiments of the lifting apparatus, the drive wheel includes a ratchet wheel, and the one-way clutch includes a pawl.

In a second aspect, the present disclosure provides a releasing apparatus for releasing a toy vehicle on a segment of a toy track having an upper end. The releasing apparatus includes a carrier, and a stop structure. The carrier movable towards the upper end of the segment of the toy track, and includes a vehicle holder including a pair of calipers. The calipers are opposed vehicle engagement surfaces. The calipers are pivotable in relation to each other to vary the calipers between a vehicle-holding configuration and a vehicle-releasing configuration. In the vehicle-holding configura-

tion, the vehicle engagement surfaces clamp the toy vehicle between the vehicle engagement surfaces to hold the toy vehicle. In the vehicle-releasing configuration, the vehicle engagement surfaces disengage from the toy vehicle to release the toy vehicle. The stop structure is attached to the toy track, and includes at least one caliper-actuating member. In use, when the carrier moves toward the upper end of the segment of the toy track relative to the stop structure (i.e. when the carrier 40 reaches the, the at least one caliper-actuating member engages at least one of the calipers to urge the calipers from the vehicle-holding configuration to the vehicle-releasing configuration.

In embodiments of the releasing apparatus, the at least one caliper-actuating member includes a pair of caliper-actuating members, and wherein, in use, each one of the caliper-actuating members engages a different one of the calipers to urge the calipers from the vehicle-holding configuration to the vehicle-releasing configuration.

In embodiments of the releasing apparatus, the toy vehicle includes a pair of wheels, and each of calipers defines a shoulder for engaging one of the wheels.

In embodiments of the releasing apparatus, the stop structure is translatable along the segment of the toy track to vary a position of the stop structure along the segment of the toy track. The stop structure may include a cam lever pivotable relative to the segment of the toy track between: a lock position in which the cam lever engages the segment of the toy track to prevent translation of the stop structure along the track; and an unlock position in which the cam lever disengages from the segment of the toy track to allow translation of the stop structure along the track. The stop structure may further include a key member movable relative to the cam lever between: a lock position in which the key member interferes with the cam lever to prevent the cam lever from pivoting from the lock position to the unlock position; and an unlock position in which the key member permits the cam lever to pivot from the lock position to the unlock position.

In embodiments of the releasing apparatus, the releasing apparatus further includes a drive wheel, a carrier line, and a one-way clutch, and optionally a support member and other features of the lifting apparatus of the first aspect and embodiments thereof, as described above

In a third aspect, the present disclosure provides a stunt selection apparatus for selecting a stunt for a toy vehicle on a toy track defining a travel direction for the toy vehicle. The stunt apparatus includes a plurality of stunt track segments, and a rotary indexer. Each of the stunt track segments is adapted to induce a motion of the toy vehicle that is different from the motion of the toy vehicle induced by the other one of the stunt track segments. The rotary indexer is attached to the stunt track segments, and is for rotating the stunt track segments about an axis that is substantially parallel to the travel direction defined by the toy track, to selectively align each one of the stunt track segments individually with the toy track such that the aligned one of the stunt track segments and the toy track form a continuous travel path for the toy vehicle.

In embodiments of the stunt apparatus, the plurality of stunt track segments may include at least three stunt track segments. The rotary indexer may further includes a knob for manually rotating the stunt track segments about the axis.

Embodiments of the apparatuses of the first, second, or third aspects, may include or be combined with features of any embodiment of the apparatus of any of the other aspects, as described above.

BRIEF DESCRIPTIONS OF THE DRAWINGS

For a better understanding of the various embodiments described herein and to show more clearly how they may be carried into effect, reference will now be made, by way of example only, to the accompanying drawings in which:

FIG. 1 is a front left perspective view of an embodiment of a toy track system of the present disclosure;

FIG. 2 is a left side elevation view of the system of FIG. 1;

FIG. 3 is a front right perspective view of the system of FIG. 1 showing the stop member at a first drop height, or alternately at a higher second drop height along the track;

FIGS. 4 to 8 show views of the carrier and stop structure of the system of FIG. 1 in various configurations, and in various positions along the track;

FIG. 4 is a front perspective view of the vehicle holder of the carrier in a vehicle-receiving configuration, while engaging the stop structure;

FIG. 5 is a front perspective view of the vehicle holder of the carrier in a vehicle-receiving configuration;

FIG. 6 is a front perspective view of the vehicle holder of the carrier in a vehicle-holding configuration, while holding a toy vehicle;

FIG. 7 is a front perspective view of the vehicle holder of the carrier in a vehicle-holding configuration, and approaching a stop member, while holding a toy vehicle;

FIG. 8 is a top perspective view of the vehicle holder of the carrier in a vehicle-holding configuration, and initially engaging the stop member, while holding a toy vehicle;

FIG. 9 is a top perspective view of the vehicle holder of the carrier in a vehicle-release configuration, while engaging the stop member, after releasing a toy vehicle;

FIG. 10A is a schematic side view of a lifting apparatus of the system of FIG. 1, showing the one-way clutch in a release position;

FIG. 10B is a schematic side view of a lifting apparatus of the system of FIG. 1, showing the one-way clutch in a holding position;

FIG. 11A is a right side perspective view of a lifting apparatus and part of the track of the system of FIG. 1;

FIG. 11B is a left side perspective view of the bracket of a support member of a lifting apparatus of FIG. 11A;

FIG. 12 is a left side perspective view of a lifting apparatus of the system of FIG. 1;

FIG. 13 is a left side perspective view of a lifting apparatus and track of another embodiment of a toy vehicle track system;

FIG. 14 is a front perspective view of the carrier of the system of FIG. 13;

FIGS. 15 to 20 show views of the stunt apparatus of the toy of FIG. 1;

FIG. 15 is a left perspective view of the stunt apparatus;

FIG. 16 is a right perspective view of the stunt apparatus;

FIG. 17 is a top front perspective view of the stunt apparatus;

FIG. 18 shows the stunt apparatus in a first orientation;

FIG. 19 shows the stunt apparatus in a second orientation;

FIG. 20 shows the stunt apparatus in a third orientation;

FIG. 21 shows the stunt apparatus with a knob;

FIGS. 22 to 24 show rear right side perspective views of different stunt track segments and motions of a toy vehicle induced by them;

FIG. 22 shows a stunt track segment for inducing a high arc jumping motion;

FIG. 23 shows a stunt track segment for inducing a forward somersault motion;

FIG. 24 shows a stunt track segment for inducing a barrel roll motion;

FIGS. 25 to 26 show perspectives view of a rotary indexer of the stunt apparatus of FIG. 15;

FIG. 25 shows the rotary indexer in a first orientation; and FIG. 26 shows the rotary indexer in a second orientation.

DETAILED DESCRIPTION

Interpretation

For simplicity and clarity of illustration, where considered appropriate, reference numerals may be repeated among the Figures to indicate corresponding or analogous elements. In addition, numerous specific details are set forth in order to provide a thorough understanding of the embodiment or embodiments described herein. However, it will be understood by those of ordinary skill in the art that the embodiments described herein may be practiced without these specific details. In other instances, well-known methods, procedures and components have not been described in detail so as not to obscure the embodiments described herein. It should be understood at the outset that, although exemplary embodiments are illustrated in the figures and described below, the principles of the present disclosure may be implemented using any number of techniques, whether currently known or not. The present disclosure should in no way be limited to the exemplary implementations and techniques illustrated in the drawings and described below.

Various terms used throughout the present description may be read and understood as follows, unless the context indicates otherwise: “or” as used throughout is inclusive, as though written “and/or”; singular articles and pronouns as used throughout include their plural forms, and vice versa; similarly, gendered pronouns include their counterpart pronouns so that pronouns should not be understood as limiting anything described herein to use, implementation, performance, etc. by a single gender; “exemplary” should be understood as “illustrative” or “exemplifying” and not necessarily as “preferred” over other embodiments. Further definitions for terms may be set out herein; these may apply to prior and subsequent instances of those terms, as will be understood from a reading of the present description. It will also be noted that the use of the term “a” or “an” will be understood to denote “at least one” in all instances unless explicitly stated otherwise or unless it would be understood to be obvious that it must mean “one”.

Modifications, additions, or omissions may be made to the systems, apparatuses, and methods described herein without departing from the scope of the disclosure. For example, the components of the systems and apparatuses may be integrated or separated. Moreover, the operations of the systems and apparatuses disclosed herein may be performed by more, fewer, or other components and the methods described may include more, fewer, or other steps. Additionally, steps may be performed in any suitable order. As used in this document, “each” refers to each member of a set or each member of a subset of a set.

As used in this document, “attached” in describing the relationship between two connected parts includes the case in which the two connected parts are “directly attached” with the two connected parts being in contact with each other, and the case in which the connected parts are “indirectly attached” and not in contact with each other, but connected by one or more intervening other part(s) between.

The embodiments of the inventions described herein are exemplary (e.g., in terms of materials, shapes, dimensions, and constructional details) and do not limit by the claims

appended hereto and any amendments made thereto. Persons skilled in the art will appreciate that there are yet more alternative implementations and modifications possible, and that the following examples are only illustrations of one or more implementations. The scope of the invention, therefore, is only to be limited by the claims appended hereto and any amendments made thereto.

Toy Track System

FIG. 1 shows a system 10 of the present disclosure for use 10 with a toy vehicle 12 that travels on a toy track 14. The toy vehicle 12 may be a wheeled toy vehicle, such as a toy truck in the embodiment shown, and may therefore have a plurality of wheels 13, including a plurality of rear wheels 204 and a plurality of front wheels 206. The track 14 includes a segment 15 having an upper end. The segment is 15 vertically extending. As used herein, “vertically extending” refers to the track 14 being oriented at a non-zero angle relative horizontal, such as about 80 degrees from the horizontal in the embodiment shown. An upper support member 16 supports the track 14 against a vertical surface 18 such as a wall or a door. A first lower support member 20 supports an intermediate portion of the track 14 on a horizontal surface 22 such as a floor or a table top. A second lower support member 24, in the form of stylized dinosaur 25 feet, supports an end of the track 14 on the horizontal surface 22. In other embodiments, the track 14 may be “free standing”—i.e. supported entirely on the horizontal surface 22 such as a floor or a table top, without the need for support against a vertical surface such as a wall or a door. A stylized 30 dinosaur head 26 houses batteries that power light-emitting diodes (LEDs) for generating lighting effects, a speaker for generating sound effects, and a motor for generating movements of the dinosaur head 26 to trap the toy vehicle 12. Accessories of the system 10 include a landing ramp 28, and 35 a smart phone holder 30. The system 10 includes a carrier 40, a stop structure 60, a lifting apparatus 80, and a stunt apparatus 110, as described below.

Carrier

With reference to FIGS. 4-9, a purpose of the carrier 40 40 is to hold the vehicle 12 as the carrier 40 is lifted along the track 14. Another purpose of the carrier 40 is to release the vehicle 12 when the carrier 40 engages the stop structure 60.

The carrier 40 is movable between a lower position, which may also be referred to as a loading position, and an upper position, which may also be referred to as a launch position (FIG. 4). In the lower or loading position, the carrier 40 is positioned for the loading of the vehicle 12 therein. In the upper position or launch position, the carrier 40 engages the stop structure 60 so as to release the vehicle 12.

The carrier 40 includes a vehicle holder that is positioned 50 for releasably holding the toy vehicle 12.

In embodiments, the vehicle holder may have any suitable structure positioned to releasably hold the toy vehicle 12. Referring to FIG. 4, in the embodiment shown, the vehicle 55 holder of the carrier 40 includes a central member 42 with a pair of attached calipers 44. The central member 42 is attached to the track 14 by means of a protrusion on the underside of the central member 42 that inserts into an elongate gap 50 defined by the track 14. The calipers 44 60 include a first caliper arm 44a and an opposed second caliper arm 44b. Each caliper arm 44a and 44b defines a vehicle engagement surface 46. In this embodiment, each of the calipers 44 is pivotally attached to the central member 42. The pivotal attachment may be by a pin connection 48, 65 thereby permitting the calipers 44 to pivot in the directions shown by the double-headed curved arrow lines. In other embodiments, only one of the calipers 44 may be pivotably

attached central member 42, while the other one of the calipers 44 is fixedly attached to a central member 42. In still other embodiments, the individual caliper arms 44a and 44b of the calipers 44 may be pivotably attached directly to one another instead of individually being pivotally mounted to a central member.

Pivoting of the calipers 44 varies the distance between their respective vehicle engagement surfaces 46 such that the calipers 44 are movable between a vehicle holding position (FIGS. 5-8) in which the calipers 44 are positioned to hold the vehicle 12 by engagement with the vehicle engagement surfaces 46 with the caliper receiving surfaces 200 on the vehicle 12, and a vehicle release position (FIG. 9) in which the vehicle engagement surfaces 46 are disengaged from the caliper receiving surfaces 200 of the vehicle 12, so as to permit launching of the vehicle 12. The calipers 44 may be biased towards the vehicle holding position. More specifically, one or more caliper-biasing members 61 (e.g. such as one compression spring or one tension spring acting between the calipers 44, or a compression spring or a tension spring or a torsion spring for each caliper arm 44a, 44b, acting between the caliper arm 44a, 44b and an anchor point on the central member 42) may be positioned to urge the calipers 44 towards the vehicle-holding position. For example, the one or more caliper-biasing members 61 may include a first torsion spring in a first one of the calipers 44 and a second torsion spring in a second one of the calipers 44. As an example, a caliper-biasing member 61 is shown in the form of a first torsion spring in a first one of the calipers 44, in FIG. 7. It will be understood that a second torsion spring may be provided in the other of the calipers 44, even though not shown in the figure.

In use, when the carrier 40 is in the loading position as shown in FIG. 5, the vehicle 12 may be loaded on the carrier 40 in any suitable way, such as by translating the vehicle 12 along the track 14 such that the vehicle 12 engages the pusher surfaces on the ends 52 of the caliper arms 44a and 44b. This causes the caliper arms 44a and 44b to separate from each other. Once the vehicle 12 has been pushed into place the caliper biasing members 61 drive the caliper arms 44a and 44b to close such that the vehicle engagement surfaces 46 engage the caliper receiving surfaces 200 of the vehicle 12.

In the embodiment shown, the caliper receiving surfaces 200 are the walls of central wells, shown at 202 in the rear wheels, shown at 204, of the vehicle 12. Alternatively however, the caliper receiving surfaces 200 may be anywhere on the vehicle 12 such as in recesses on the vehicle body.

When the carrier 40 is in a vehicle-holding configuration as shown in FIGS. 6, 7 and 8, the opposed vehicle engagement surfaces 46 engage the tires of the vehicle 12. In this embodiment, the calipers 44 define shoulders 54 that are complementary in shape to the wheel of the vehicle 12. Engagement of the shoulders 54 with the wheel helps the calipers 44 to more securely hold the vehicle 12.

Alternatively, the calipers 44 may be biased towards the vehicle-holding configuration without the need for springs or the like, by their shape, such that gravity urges them towards the vehicle-holding configuration.

Stop Structure

A purpose of the stop structure 60 is to limit the travel of the carrier 40 on the track 14, and thus the "drop height" on the track 14 from which the vehicle 12 can be released. In embodiments, another purpose of the stop structure 60 is to actuate the carrier 40 from the vehicle-holding configuration

to the vehicle-releasing configuration to release the vehicle 12 to roll down the track 14, as discussed above.

In embodiments, the stop structure may have different member(s) that are adapted to engage the vehicle holder of the carrier 40. Referring to FIG. 4, in the embodiment shown, the stop structure 60 includes a main stop structure body 62, a cam lever 64, a key member 66, and a pair of caliper-actuating members 68, as described below.

The main stop structure body 62 is attached to the track

- 10 14. The main stop structure body 62 is translatable along the toy track 14 to vary the position of the stop structure 60 along the toy track 14, but can be fixed in position using the cam lever 64 and key member 66. The cam lever 64 and the key member 66 are both associated with lock positions and unlock positions. In their lock positions as shown in FIG. 4, the cam lever 64 engages the underlying track 14 through an aperture defined by the main stop structure body 62. Friction between the cam lever 64 and the track 14 prevents translation of the main stop structure body 62 relative to the track
- 15 14. The key member 66 interferes with the cam lever 64 to prevent the cam lever 64 from pivoting from the lock position to the unlock position. In this manner, the key member 66 acts as a safety device. In order to adjust the position of the stop structure 60 along the track 14, the user moves the key member 66 to the unlock position by shifting the key member 66 leftward relative to the main stop structure body 62, as shown by the straight directional arrow 70 in FIG. 4. The key member 66 is shaped such that, in the unlock position, it permits pivoting moving of the cam lever
- 20 64. The user can then pivot the cam lever 64 downward relative to the main stop structure body 62 to the unlock position, as shown by the curved directional arrow 72 in FIG. 4. The cam lever 64 is shaped such that, in the unlock position, the cam lever 64 disengages from the track 14. The user can then slide the stop structure 60 along the track 14 to control the desired maximum "drop height" of the carrier 40, and then fix the position of the stop structure 60 by moving the cam lever 64 and the key member 66 to their lock positions. Referring to FIG. 3, for example, the stop
- 25 30 40 structure 60 can be fixed in position on the track 14 to select a drop height of 4 feet (1.2 meters) or 6 feet (1.8 meters) above a horizontal surface 22 such as a floor.

Referring to FIG. 4, each of the caliper-actuating members 68 is associated with a different one of the pivotable

- 45 calipers 44 of the carrier 40. In other embodiments of the carrier 40 having only one pivotable caliper 44, the stop structure 60 may have only one caliper-actuating member 68. In this embodiment, each of the caliper-actuating members 68 has an elongate triangular shape extending downward to a vertex. Referring to FIGS. 4, 7 and 8, the vertices of the caliper-actuating members 68 are positioned to engage sloped upper surfaces of the calipers 44 of the carrier 40. Referring to FIG. 9, the stop structure 60 is fixed in position along the track 14. As the carrier 40 moves up along the track 14 relative to the stop structure 60, the caliper-actuating members 68 urge the calipers 44 to pivot relative to the central member 42 of the carrier 40, in the direction shown by the curved arrows, into the vehicle-releasing configuration. This pivoting increases the distance between the opposed vehicle engagement surfaces 46, so that they disengage from the vehicle 12, and release the vehicle 12 to roll down the track 14.

above. The lifting apparatus 80 may be used to lift the vehicle 12 beyond the reach of a user. Referring to FIG. 1, for example, the child 150 may use the lifting apparatus 80 within the child's reach to lift the carrier 40 and the held vehicle 12 to the upper end of the track 14 at about 6 feet (1.8 meters) above the horizontal surface 22.

FIG. 10A shows a schematic representation of a lifting apparatus 80. In this embodiment, the lifting apparatus 80 includes a support member 82, a drive wheel 84, a one-way clutch 85, and a carrier line 86. These and other parts of the lifting apparatus 80 are described below. FIGS. 11 and 12 show one embodiment of the lifting apparatus 80, and FIG. 13 shows another embodiment of the lifting apparatus 80.

The support member 82 may be provided to rotatably support the drive wheel 84. In other embodiments, the support member 82 may be omitted, if for example, the drive wheel 84 is directly attached and rotatably attached to the track 14. In embodiments, the support member 82 is positioned to hold the track 14. In the embodiment shown, the support member 82 is also adapted to bear against a vertical surface 18 such as a wall. FIGS. 11A, 11B and 12 show one embodiment of a support member 82 including three parts. The first part is a bracket 88 that has a planar surface that interfaces with the vertical surface 18. As shown in FIG. 11B, the bracket may be attached to the vertical surface 18 using strips of stretch releasing adhesive tape 89, such as tape marketed under the name Command Strips™ (3M Company; USA). The second part is a substantially triangular-shaped frame 90 that releasably attaches to the bracket 88 by interference fit of tabs defined by the bracket 88 that insert into corresponding slots defined by the frame 90. The third part is a truss 92 that releasably attaches to the frame 90 by interference fit of tabs defined by the truss 92 that insert into corresponding slots defined by the frame 90. In this embodiment, the support member 82 is disposed above the horizontal surface 22 (e.g., floor) that supports the track and does not contact the horizontal surface 22.

In the embodiments shown, the drive wheel 84 is rotatably supported by the support member 82. The drive wheel 84 is rotatable to pull the carrier line 86, which in turn drives the carrier 40 towards the launch position. In the embodiment shown in FIGS. 10A, 10B, 11A, 12 and 13, the drive wheel 84 is disposed horizontally adjacent to the vertical surface 18 of the wall, and more particularly, horizontally between the vertical surface 18 of the wall and the track 14. This is advantageous in that the drive wheel 84 does not impede the user's view of the track 14, and conserves space. Referring to FIG. 10A, the drive wheel 84 is rotatable in a first drive wheel direction D1, about an axis that is transverse to the elongate direction of the track 14.

The one-way clutch 85 may have any suitable structure. In the embodiment shown, the one-way clutch includes a plurality of teeth 98, which may optionally be near a periphery of the drive wheel 84. In the embodiment shown in FIGS. 10A and 10B, the teeth 98 extend across the entire thickness of the drive wheel 84. In the embodiment shown in FIGS. 11A and 12 the teeth 98 do not extend across the entire thickness of the drive wheel 84, but are instead flanked by a flange on one side thereof. A handle 87 is attached to the drive wheel 84 for manually rotating the drive wheel 84.

The one way clutch 85 further includes a pawl 85a that engages the plurality of teeth 98 on the drive wheel 84. Worded more broadly, a plurality of teeth 98 are driven to rotate due to rotation of the drive wheel 84. The pawl 85a is positioned to engage the plurality of teeth 98 to prevent rotation of the drive wheel 84 in a second rotational direction

D2 that is opposite the first rotational direction. In the embodiment shown, the pawl 85a is positioned to be pushed away by the teeth 85b during rotation of the drive wheel 84 in the first rotational direction D1 (i.e. a counter-clockwise direction in the view shown in FIGS. 10A and 10B), which is the direction in which to drive the carrier 40 towards the launch position. Thus, the pawl 85a permits rotation of the drive wheel 84 in the first rotational direction D1. The pawl 85b is positioned to engage the teeth 85b thereby blocking rotation of the drive wheel 84, during rotation of the drive wheel 84 in the second rotational direction D2 (i.e. clockwise in the view shown in FIGS. 10A and 10B) so as to permit the user, while cranking the handle 87 to drive the carrier 40 towards the launch position, to let go of the handle 87 momentarily, without the carrier 40 falling all the way down to its bottom-most position. Then the user can regrip the handle 87 to continue rotating the drive wheel 84 in the first rotational direction D1 so as to continue driving the carrier 40 towards the launch position. When the pawl 85a is engaged with the teeth 98 to prevent rotation of the drive wheel 84 in the second rotational direction D2 (i.e. when the drive wheel 84 is attempted to be rotated in the second rotational direction D2), the pawl 85a may be said to be in a holding position (FIG. 10B). When the drive wheel 84 is rotated in the first rotational direction D1 and therefore the pawl 85a is positioned such that the pawl 85a permits the rotation of the drive wheel 84 in the first rotational direction D1, the pawl 85a may be said to be in a release position (FIG. 10A). Based on the above, the one-way clutch 85 may be said to permit rotation of the drive wheel 84 in the first rotational direction D1, and to prevent rotation of the drive wheel 84 in the second rotational direction D2.

While the one-way clutch operated by interference of the pawl 85a with the drive wheel 84, in other embodiments, the pawl 85a may instead resist movement of the drive wheel 84 by frictional engagement with the drive wheel 84 or with the carrier line 86. For example, the pawl 85a may be shaped in the form of a cam that is rotated into progressive tighter engagement with the drive wheel 84 or with the carrier line 86 by rotation of the drive wheel 84 in the second rotational direction D2, so as to stop further rotation of the drive wheel 84 in the second rotational direction D2.

FIG. 13 shows another embodiment of a support member 82 that includes parts in the shape of a pair of stylized dinosaur feet 94 that bear against the vertical surface 18, and legs 96 that extend horizontally toward the track 14. In this embodiment, the legs 96 are attached to the track 14, and therefore the support member 82 at least partially supports the track 14. In still other embodiments, the support member 82 may have different forms.

The carrier line 86 may be a flexible member, with non-limiting examples being a cord, a string, a ribbon, a chain, a cable, or the like. The carrier line 86 is engaged with the drive wheel 84 and attached to the carrier 40. Referring to FIG. 10, the carrier line 86 may be routed around a sheave 100 or similar structured attached to the track 14 near its upper end. Such a sheave 100 may not necessary if the drive wheel 84 is disposed above the desired drop height of the vehicle 12. Referring to the embodiment shown in FIG. 13, the carrier line 86 is engaged with the drive wheel 84 by being tied to a stud 102 that is attached to the drive wheel 84. Referring to the embodiment shown in FIG. 14, for example, the carrier line 86 is engaged with the carrier 40 by being tied to a stud 104 that is attached to the carrier 40, and received in the gap 50 defined by the track 14. In other embodiments, the carrier line 86 may be engaged with the drive wheel 84 and

the carrier **40** in different ways. For example, the drive wheel **84** may be attached to a winch drum connected to a drive wheel **84**, and the carrier line **86** may be wound around the winch drum. In either case, when the drive wheel **84** is rotated relative to the support member **82** in the first wheel direction, the drive wheel **84** pulls the carrier line **86** to move in the first carrier line direction, which turns pulls the carrier **40** and the held vehicle **12** up the track **14**.

Stunt Apparatus

A purpose of the stunt apparatus **110** is to allow a plurality of different stunt track segments to be selectively and individually aligned with the track **14**. FIGS. **15** to **21** show one embodiment of a stunt apparatus **110**. FIGS. **22** to **24** show different stunt track segments. The stunt apparatus **110** includes a plurality of stunt track segments attached to a rotary indexer **142**, as described below.

As used herein, a “stunt track segment” refers to a segment of toy track that is adapted to induce a motion of the vehicle **12** when the vehicle **12** travels over the stunt track segment. The plurality of stunt track segments may be any integer number of stunt track segments greater or equal to two stunt track segments. In the embodiments shown in the Figures, the stunt apparatus **110** includes three stunt track segments. As shown in FIGS. **18** and **22**, a first stunt track segment **112** has an upwardly curved ramp surface for inducing a “high arc” jumping motion to the vehicle **12** as shown by the curved arrow line **113**. As shown in FIGS. **19** and **23**, a second stunt track segment **114** has a first portion **116** and a second portion **118** pivotably connected thereto by a pin **120**. As the vehicle **12** passes over a trigger mechanism **122** (FIG. **19**) of the second stunt track segment **114**, a biasing spring (not shown) such as a torsion spring, is released and actuates the second portion **118** to pivot upwardly about an axis transverse to the travel direction along the track **14** as shown by the curved arrow line **124** (FIG. **23**) and thereby “kick” the vehicle **12** into a forward somersault motion as shown by the curved arrow line **126** (FIG. **23**). As shown in FIGS. **20** and **24**, a third stunt track segment **128** has a first portion **130** and a second portion **132** pivotably connected thereto by a pin **134**. As the vehicle **12** passes over a trigger mechanism **136** (FIG. **20**) of the third stunt track segment **128**, a biasing spring (not shown) such as a torsion spring, is released and actuates the second portion **132** to pivot upwardly about an axis transverse to the travel direction along the track **14** as shown by the curved arrow line **138** (FIG. **24**) and thereby “kick” the vehicle **12** into a barrel roll motion as shown by the curved arrow line **140** (FIG. **24**). In other embodiments, the stunt apparatus **110** may include additional or alternative stunt track segments for inducing different types of motions.

As used herein, “rotary indexer” refers to a device having a first part and a second part attached to the first part and rotatable relative to the first part to a plurality of pre-defined positions. As an example, FIGS. **25** and **26** show an embodiment of a rotary indexer **152** having a substantially cylindrical first part **152** that inserts into substantially tubular second part **154**. The second part **154** defines slots (FIG. **25**) that receive tabs angularly distributed on the surface of the first part **152** to fix rotation of the second part in a plurality of pre-defined orientations relative to the first part **152**, including a first orientation shown in FIG. **25**, and a second orientation shown in FIG. **26**.

Referring to FIGS. **15** to **17**, the plurality of stunt track segments are attached to the rotary indexer **142**. The track **14** defines a travel direction for the toy vehicle **12** as shown by the directional arrow **144**. The rotary indexer **142** permits the stunt track segments to be rotated, as shown by the

curved directional arrow **146**, about an axis that is substantially parallel to the travel direction, to selectively align each one of the stunt track segments individually with the track **14**. That is, the track **14** and the aligned stunt track segment form a continuous travel path for the vehicle **12**, even though there may be a small gap **50** between them. FIGS. **18**, **19**, and **20** show the rotary indexer **142** in first, second and third orientations, respectively, in which the first, second and third stunt track segments **112**, **114**, **128**, respectively, are aligned with the track **14**. FIG. **21** shows a knob **148** attached to the rotary indexer **142** to facilitate rotating the stunt track segments.

By virtue of the stunt track segments being rotatable about an axis that is substantially parallel to the travel direction defined by the track **14**, the stunt apparatus **110** as a whole has a relatively compact configuration. This allows the stunt apparatus **110** to be placed within the confines of a part such as the stylized dinosaur head **26** with the stunt track **14** elements projecting outwardly in a tongue-like fashion, as shown in FIG. **1**.

PARTS LIST

- 10** system
- 12** toy vehicle
- 13** toy vehicle, wheel

What is claimed is:

1. A lifting apparatus for lifting a toy vehicle along a segment of a toy track, the segment having an upper end, the lifting apparatus comprising:
  - a carrier including a vehicle holder that is positioned for holding the toy vehicle, wherein the carrier is movable towards the upper end of the segment and is releasably connectable to the toy vehicle;
  - a drive wheel rotatable relative to the segment;
  - a carrier line that is attached to the carrier and which is engageable with the drive wheel such that rotation of the drive wheel in a first drive wheel direction drives the carrier line to travel in a first carrier line direction so as to lift the carrier and the toy vehicle towards the upper end of the segment; and
  - a one-way clutch that is positionable in a release position to permit the carrier line to move in the first carrier line direction so as to permit lifting of the carrier, and is positionable in a holding position to resist movement of the carrier line in a second carrier line direction that is opposite to the first carrier line direction so as to hold the carrier against dropping.
2. The lifting apparatus of claim 1, wherein the lifting apparatus further comprises a support member that supports either the drive wheel or the toy track, or both, wherein the support member bears against a vertical surface, and, wherein at least part of the drive wheel is disposed horizontally between the segment of the toy track and the vertical surface.
3. The lifting apparatus of claim 1, wherein the lifting apparatus further comprises a support member that rotatably

supports the drive wheel, wherein the toy track is supported on a horizontal surface, and wherein the support member does not contact the horizontal surface.

4. The lifting apparatus of claim 1, wherein the lifting apparatus further comprises a support member that rotatably supports the drive wheel, and wherein the support member at least partially supports the toy track.
5. The lifting apparatus of claim 1, wherein the lifting apparatus further comprises a support member that rotatably supports the drive wheel, and wherein the support member is removably attached to a vertical surface adjacent to the segment of the toy track.
- 10 6. The lifting apparatus of claim 5, wherein the support member comprises a first part comprising a planar surface that is removably attached to the vertical surface, and a second part extending horizontally from the first part and releasably attached by interference fit to the first part.
- 15 7. The lifting apparatus of claim 5, wherein the support member is removably attached to the vertical surface by stretch releasing adhesive tape.
8. The lifting apparatus of claim 1, wherein the lifting apparatus further comprises a handle for manually rotating the drive wheel.
- 20 9. The lifting apparatus of claim 1, wherein the lifting apparatus further comprises the segment of the toy track, and wherein the toy track defines a gap for receiving the carrier line.
- 25 10. The lifting apparatus of claim 1, wherein the drive wheel comprises a ratchet wheel, and the one-way clutch comprises a pawl.
11. A releasing apparatus for releasing a toy vehicle on a segment of a toy track, the segment having an upper end, the releasing apparatus comprising:
  - 30 a carrier movable towards the upper end of the segment, and including a vehicle holder comprises a pair of calipers comprising opposed vehicle engagement surfaces, wherein the calipers are pivotable in relation to each other to vary the calipers between:
    - 35 a vehicle-holding configuration in which the vehicle engagement surfaces clamp the toy vehicle between the vehicle engagement surfaces to hold the toy vehicle; and
    - 40 a vehicle-releasing configuration in which the vehicle engagement surfaces disengage from the toy vehicle to release the toy vehicle; and
    - 45 a stop structure attached to the toy track, and comprising at least one caliper-actuating member; and
  - 50 wherein, in use, when the carrier moves towards the upper end of the segment of the toy track relative to the stop structure, the at least one caliper-actuating member engages at least one of the calipers to urge the calipers from the vehicle-holding configuration to the vehicle-releasing configuration.
- 55 12. The releasing apparatus of claim 11, wherein the at least one caliper-actuating member comprises a pair of caliper-actuating members, and wherein, in use, each one of the caliper-actuating members engages a different one of the calipers to urge the calipers from the vehicle-holding configuration to the vehicle-releasing configuration.
13. The releasing apparatus of claim 11, wherein the toy vehicle comprises a pair of wheels, and wherein each of the calipers defines a shoulder for engaging one of the wheels.
- 60 14. The releasing apparatus of claim 11, wherein the stop structure is translatable along the segment of the toy track to vary a position of the stop structure along segment of the toy track.

15

15. The releasing apparatus of claim 14, wherein the stop structure comprises a cam lever pivotable relative to segment of the toy track between:

a lock position in which the cam lever engages the toy track to prevent translation of the stop structure along the segment of the toy track; and

an unlock position in which the cam lever disengages from segment of the toy track to allow translation of the stop structure along segment of the toy track.

16. The releasing apparatus of claim 15, wherein the stop structure comprises a key member movable relative to the cam lever between:

a lock position in which the key member interferes with the cam lever to prevent the cam lever from pivoting from the lock position to the unlock position; and

an unlock position in which the key member permits the cam lever to pivot from the lock position to the unlock position.

17. The releasing apparatus of claim 11, wherein the releasing apparatus further comprises:

16

a drive wheel rotatable relative to the segment of the toy track;

a carrier line attached to the carrier and which is engageable with the drive wheel such that rotation of the drive wheel in a first drive wheel direction drives the carrier line to travel in a first carrier line direction so as to lift the carrier and the toy vehicle towards the upper end of the segment; and

a one-way clutch that is positionable in a release position to permit the carrier line to move in the first carrier line direction so as to lift the carrier and the toy vehicle toward the stop structure, and is positionable in a holding position to resist movement of the carrier line in a second carrier line direction that is opposite to the first carrier line direction so as to hold the carrier against dropping.

18. The releasing apparatus of claim 17, wherein at least part of the drive wheel is disposed horizontally adjacent to the segment of the toy track.
